UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 12,323, dated June 21, 1881.

Application filed May 6, 1881. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to 10 which reference is made; and it consists of an unshaded letter, the terminations at the top and bottom of which are provided with the inclined sides, as shown, and the cross-lines of 15 which letters are composed of the inclined line, as shown.

In the A, H, M, and N one of the up-and-down portions of the letter may be made larger and extending below the other up-and-down portion. In the N, V, W, X, and Y one of the 20 up-and-down portions of the letter is made larger and extending above the other up-and-down portion. In the C and G the upper right terminations consist of a line curved outward and terminating in the heavy dots. The lower 25 right-hand termination of the C is curved in one direction to the right, in the other to the left. In the G the lower termination on the right is extended below the line and curved to the right, and the cross-termination extends 30 inward and has the inclined side termination below it on the left. In the J the up-and-down portion of the letter is extended below the line, and the left-hand lower termination consists of the short line with ball termina- 35 tion at the top. In the K the lower termina- 35 tion upon the right is below the line. The tail of the Q consists of the inclined line gradually extended at top and bottom, and having these portions inclined, as shown, and ex-

tended upon the left. The lower portion of the R, upon the right, is extended below the line, and at its base is widened, and the sides inclined. The upper right and lower left hand terminations of the S have the curved line with dot terminations. 40

The design is preserved in the lower-case and figures, the a, f, r, s, and t having the curved line with ball terminations, the upper right-hand termination of the c terminating in a dot, the lower terminations of the g and j being curved, and that of the g having upon the left a triangular-pointed figure, and that of the j having a similar termination. The lower right-hand terminations of the h, k, and m are extended below the line, and in the h and m 55 gradually widen at the base, and are followed by a horizontal line upon the left. In the v and w the upper left-hand portions are extended above the line. In the x the right-hand up-and-down portion extends below the line 60 and is inclined at its base. In the y the right-hand up-and-down portion above the line is inclined on its upper side and curves below the line upon the left, and has the pointed triangular termination. In the figures 1, 3, and 65 5 the inclined terminations are found, and in the 2 the lower right-hand termination is the curved line with dot termination upon its upper end. 50

Having now set forth my invention, what I claim as new is—

The design for a font of printing-types, as shown and described.

HERMAN IHLENBURG.

In presence of—

E. F. HUCK,
HERMAN METIUS.
